UNITED STATES PATENT OFFICE.

HARRY LOUIS MILLER, OF PITTSBURGH, PENNSYLVANIA.

SIGNAL FOR MOVING-PICTURE REELS.

1,214,268.

Specification of Letters Patent. Patented Jan. 30, 1917.

Application filed June 25, 1915. Serial No. 36,385.

To all whom it may concern:

Be it known that I, HARRY L. MILLER, a citizen of the United States, residing at Pittsburgh, in the county of Allegheny and State of Pennsylvania, have invented certain new and useful Improvements in Signals for Moving-Picture Reels, of which the following is a specification.

This invention relates to an improved signal which is used in connection with the reel of a moving picture machine and the principal object of the invention is to provide a signal so constructed as to warn the operator when the reel is almost emptied of the film wound thereon thus permitting the operator of a second machine to get ready to show up his machine. By use of this device the curtain will never be left blank as the operator of the second machine will get his machine ready for use as soon as the signal is given and can immediately start operation when the reel of the first machine is completely un wound.

Another object of the invention is to provide a device so constructed as to permit it to be easily connected with machine already in use.

Another object of the invention is to provide a device which is so constructed that the contact pin carried by the movable stem will be sure to enter the opening carrying the contact point or block with which the stationary contact is connected.

Another object of the invention is to provide means for releasably holding the stem in a raised position when putting a new reel or film in place.

This invention is illustrated in the accompanying drawings, wherein:

Figure 1 is a sectional view showing the signal in place and with the stem resting upon a filled reel. Fig. 2 is a view similar to Fig. 1 showing the stem lowered to bring the contact carried by the stem into engagement with the contact block of the stationary contact member. Fig. 3 is a vertical sectional view taken along the line 3-3 of Fig. 1 with the stem shown in elevation.

The housing or tube 10 of this signal in which the stem 11 is slidably mounted is provided with an enlarged base 12 having a flange 13 through which the bolts or fasteners 14 pass to connect the housing with the box 15 in which is rotatably mounted the reel 16. This stem 11 is provided at its lower end with a harp 17 which is con-

structed somewhat similar to a trolley harp and carries rollers 18 which rest upon the film 19 wound upon the reel. Therefore the reel can turn readily with the stem gradually moving downwardly as the film is unrolled. A latch 20 is secured to the tube or housing and is adapted to pass through the opening 21 in the housing to fit into the notch or cutout 22 of the stem thus permitting the stem to be releasably held in a raised position while putting in a new reel or film. After the reel is in place the latch can be moved to the position shown in Figs. 1 and 2 thus releasing the stem and permitting it to drop into engagement with the film.

At one side of the base 12 there is provided a block 23 which is formed of insulating material and is provided with a passageway 24 permitting access to a contact point or block 25 embedded in the insulating block 23. This block 23 is held in place by the screw or fastener 26 and is positioned so that when the stem 11 moves downwardly from the position shown in Fig. 1 to the position shown in Fig. 2 the contact pin 27 carried by the arm 28 extending from the stem 11 through the slot 29 of the housing will pass into the passageway 24 and contact with the contact point or block 25. The stationary contact pin 30 extends through the block 23 to engage the point 25 and therefore when the pin is in the position shown in Fig. 2 current can pass from one pin to the other through the block 25.

The battery 31 which forms the source of power for the signal is connected with the contact point 27 by means of the wire 32 and is connected with the switch 33 by means of the wire 34. The wire 35 which leads from the contact pin 30 and wire 36 which leads from the switch 33 are connected with the signal 37 which will be a light but which may be any other type desired. From an inspection of Figs. 1 and 2 it will readily be seen that when the device is in the position shown in Fig. 1 the circuit will be broken and the light will not be illuminated and that when the device is in the position shown in Fig. 2 the circuit will be closed and the light illuminated. It will also be seen that after the light has been illuminated the switch can be opened thus breaking the circuit and preventing the electricity from being wasted.

When putting this device in place it is

simply necessary to form an opening in the top of the usual film box to permit the stem 11 and harp 17 to pass through the same and to then secure the housing 10 and block 23 to the film box. The connection for the battery and signal can then be easily made and the device is ready for use. The rollers will rest upon the film and as the film is unwound from the upper reel onto the lower one, which does not need to be shown, the stem will move downward until it reaches the position shown in Fig. 2. In this position the signal light will be illuminated thus indicating to the operator of the second machine that it is time to get his machine ready for use.

It will be seen that this device is very simple in construction but that it will be very effective in operation and that it will not easily get out of order or need repair. It will be further noted that this stem 11 by having its rollers rest upon the film will to a certain extent act as means for preventing the film from running loose upon the reel and therefore it will serve as brake means for the film.

What is claimed is:—

1. A device of the character described comprising a tubular housing having an attaching base and provided with a longitudinally extending slot, a stem slidably

mounted in said housing, a harp connected with the lower end of said stem, rollers carried by said harp, an insulating block connected with said housing, a contact point embedded in said block, said block being provided with a passageway for communication with said point, a stationary contact pin embedded in said block and contacting with said contact point, an arm extending from said stem through the slot in said housing, and a contact pin carried by said arm and passing through the passageway of said block to contact with said contact point.

2. A device of the character described comprising a housing provided with a longitudinally extending slot, a stem slidably mounted in said housing, a roller connected with the lower end of said stem, a contact point insulated from said housing, a stationary contact pin engaging said contact point, an arm extending from said stem through the slot in said housing, and a contact pin carried by said arm to engage said contact point.

In testimony whereof I affix my signature in presence of two witnesses.

HARRY LOUIS MILLER.
